United States Patent Office.

JOHN G. CROSS, OF BRATTLEBORO, VERMONT.

Letters Patent No. 79,054, dated June 23, 1868.

IMPROVEMENT IN RAILWAYS.

The Schedule referred to in these Letters Patent and making part of the same.

TO ALL WHOM IT MAY CONCERN:

Be it known that I, JOHN G. CROSS, of Brattleboro, in the county of Windham, and State of Vermont, have invented a new and useful Improvement in Railway-Structure; and I do hereby declare that the following is a full, clear, and exact description thereof, which will enable those skilled in the art to make and use the same, reference being had to the accompanying drawings, forming part of this specification.

Figure 1 is a top view of a portion of a railway-track illustrating my improvement.

Figure 2 is a top view of a portion of a railroad-track showing a modification of my improvement.

Figure 3 is a detail cross-section of the same, taken through the line $x\ x$, fig. 2.

Figure 4 is a detail cross-section of the same, taken through the line $y\ y$, fig. 1.

Figure 5 is a side view of the outer side of a portion of the same.

Figure 6 is a side view of the inner side of a portion of the same.

Figure 7 is a view of one of the bolts.

Similar letters of reference indicate corresponding parts.

My improvement has for its object to improve the construction of railroad-rails and chairs, so as to enable the rails to be made stronger and lighter, and so as to make the surface of the track continuous; and it consists in the construction of the rails and chairs, and in the combination of the various parts with each other, as hereinafter more fully described.

A are the rails, the ends of which are halved vertically, as shown in figs. 1 and 4, so as to overlap and fit upon each other. The heads a^1 of the rails A, are made round in their general form, with flat top surfaces for the wheels to roll upon. The central part, a^2 , of the rails A, is made thin where it joins the head a^1 , and becomes gradually thicker as it descends to where more strength is required. The lower part of the rails is branched or arched, as shown in figs. 3 and 4, so as to give a broad, firm base to said rails.

B are the chairs, which rest upon two ties laid side by side, and a short distance apart, as shown in figs. 1 and 5. The chairs are made with lips, b^1 , upon their inner sides, which fit over the inner edges of the bases of two contiguous rails. The outer lips, b^2 , of the chairs B, are extended up to the top of the rails A, so as to form a sub-rail, C, for the car-wheels to roll upon when passing from one rail to another, so that the bearings for the wheels may be continuous. The inner side of the sub-rail C should be so formed as to fit the outer sides of the rails, the ends of which it overlaps.

If desired, the sub-rail C may be made separate from the lip b^2 of the chairs B, as shown in figs. 2, 3, and 5. In this case a lug, b^3 , is formed upon the lip b^2 , which enters an opening or notch in the lower edge of the sub-rail C, to hold it securely in place and prevent longitudinal movement.

D are the bolts, by which the sub-rails are secured to the rails A. The bolts D pass through slots in the ends of the rails A, and through holes in the sub-rails C, so as to allow the main rails to expand and contract with changes of temperature, and to guard against the slip of the rails caused by the draw of the drive-wheels, which, in double-track roads, where the travel upon each track is always in one direction, is very great when the rails are secured in the ordinary manner. The heads of the bolts D are made oblong, as shown in fig. 7, to prevent them from turning when in place, and also to cover the slots or oblong holes in the rails A. The bolts D are secured in place by the wedge-keys E, as shown in figs. 4 and 5.

Having thus described my invention, I claim as new, and desire to secure by Letters Patent—

1. The rails A, formed with rounded heads and branched or arched bases, and having their ends halved vertically to overlap and fit upon each other, substantially as herein shown and described, and for the purpose set forth.

2. The combination of the two-tie chair B, having a sub-rail, C, formed upon or attached to it, with the overlapped ends of the contiguous rails A, substantially as herein shown and described, and for the purpose set forth.

3. The sub-rail C, made solid with and upon the chair B, substantially as herein shown and described, and for the purpose set forth.

4. The detachable sub-rail C, secured to the chair B by means of the lug b^3 , formed upon the outer lip b^2 of said chair, and entering a notch or opening in the lower edge of said sub-rail, substantially as herein shown and described.

5. The ends of the main rail A, having its ends secured to the sub-rail C and to the chair B by the bolts D and wedge-keys E, substantially in the manner herein shown and described, and for the purpose set forth.

The above specification of my invention signed by me, this 9th day of December, 1867.

JOHN G. CROSS.
